UNITED STATES PATENT OFFICE.

ALEXANDER H. WELKER, OF BERLIN, ONTARIO, CANADA, ASSIGNOR TO THE HAWTHORNE MANUFACTURING COMPANY, INC., OF BRIDGEPORT, CONNECTICUT, A CORPORATION OF CONNECTICUT.

ACOUSTIC APPARATUS.

1,175,850.

Specification of Letters Patent. Patented Mar. 14, 1916.

Application filed February 5, 1913. Serial No. 746,348.

To all whom it may concern:

Be it known that I, ALEXANDER H. WELKER, a subject of the King of England, and a resident of Berlin, in the Province of 5 Ontario and Dominion of Canada, have invented an Improvement in Acoustic Apparatus, of which the following description, in connection with the accompanying drawings, is a specification, like characters on the 10 drawings representing like parts.

This invention relates to acoustic apparatus and more especially, though not exclusively, to mechanically actuated diaphragm horns, and will be best understood 15 by reference to the following specification when taken in connection with the accompanying drawings of one illustrative embodiment thereof, while its scope will be more particularly pointed out in the appended claims.

In the drawings: Figure 1 is a central, longitudinal section of an acoustic apparatus embodying my invention; Fig. 2 is a rear elevation of the apparatus as 25 viewed from the right hand side of Fig. 1; and Fig. 3 is a detail, sectional view on a line 3—3 of Fig. 1.

Referring to the drawings and to the embodiment of my invention which I have 30 there shown for illustrative purposes, 4 is a vibratory body, preferably in the form of a metallic diaphragm, having its marginal portion secured to a suitable mounting 5, herein consisting of a casing comprising a 35 back 6, a front 7 and an intermediate ring 8 united by a plurality of screws 9 passing through all three parts of the casing and through the diaphragm, thus serving not only to secure the diaphragm but to fasten 40 the parts of the casing together.

The front member 7 of the casing is provided with an aperture 10, through which the sound waves produced by the diaphragm are delivered, and I preferably employ a 45 suitable resonator or horn 11, communicating with said aperture. Herein, the resonator 11 is in the form of a thin tube encircling the forward end of the front member 7 of the casing, and fixed thereto in any 50 suitable manner, as by soldering. As a means for excluding dust and other foreign substances from the interior of the casing 5, I preferably provide a screen 12 disposed

across the front of the aperture 10 and held in place by a retaining ring 13. Located at 55 the back of the casing 5 is a bearing member 14 provided with a hub 15 passing through and swiveled in a bearing 16 provided in the back member 6 of the casing, and held in place therein by suitable means, 60 herein a washer 17, secured to the hub by screws 18. For convenience of manufacture and assembling the parts, the bearing member 14 is formed in two parts, a casing or support 19 and a bearing member proper 20, the latter being provided with a shoudered stem 21 projecting into the former and secured therein by suitable means, herein a set screw 22. Eccentrically journaled in the part 20 of the bearing member 14 is 70 a power shaft 23 suitably connected to the diaphragm 4 to impart a vibratory motion thereto. In the present instance, the vibration is produced by a cam 24 secured to the shaft 23, and having a suitable irregularly 75 formed periphery coöperating with a plunger hammer 25 interposed between the cam and the diaphragm, and mounted to slide loosely in a guideway 26 provided in the hub 15. Preferably, the end of the 80 hammer which coöperates with the cam is provided with a suitably rounded point, which in practice will be hardened, as will also the cam, so that it will stand the great wear to which it is subjected. 85

It will now be evident that if the power shaft 23 be rotated at high speed, the rotation of the cam 24 will cause the hammer 25 to strike the diaphragm 4 with a continuous series of rapidly recurring blows, thus 90 vibrating or displacing the diaphragm in a direction at right angles to its plane and setting up vibrations which will cause the production of sound waves, the latter issuing through the aperture 10 and through 95 the resonator 11. While the shaft 23 may be rotated by any other suitable power means, it is herein provided with a driving member 27 in the form of a friction disk of rubber, leather, or other suitable yielding 100 material, clamped between two plates 28 and 29, and secured in any suitable manner to the shaft, as by means of a nut 30 threaded onto the latter, and clamping the disk against the shoulder 31 on the shaft. The 105 driving member 27 is intended to directly

coöperate with some suitable frictional driving means, as for example the wheel of a vehicle, and is intended to be moved into and out of driving engagement therewith by 5 swinging the swiveled bearing member 14 to and fro. To this end, the apparatus may be rigidly fixed to the vehicle in any suitable manner, as by providing the ring 8 with an attaching lug or ear 32, which may be 10 fixed to any convenient part of the vehicle, and the bearing member 14 is swung to and fro by suitable manually operable means, herein a cord or other flexible connection 33 attached to a ring 34 encircling the part 20 15 and swiveled in a groove 35 provided in the latter. As a means for normally holding the driving member 27 out of contact with the wheel by which it is driven, there may be provided suitable yielding means, herein 20 a spring 36, secured at one end to the ring 34 and at its other end to a fixed lug 37. This forms a simple, convenient, and effective means for applying the power of the vehicle wheel directly to the power shaft of 25 the apparatus without the use of any intermediate flexible or other connection.

The part 19 of the bearing member 14 provides a chamber or casing 38 serving to inclose the cam 24 and the rear end of the 30 hammer 25 to protect the same from dust, dirt and water and to provide a lubricating chamber which may contain a suitable lubricant. By simply removing the screw 22 and withdrawing the part 20 of the bearing 35 member 14, the cam may be withdrawn from its chamber for purposes of inspection, and to renew the lubricant. By loosening the screw 22, the bearing member 20 may be turned thereby to adjust the cam 24 with 40 relation to the hammer 25 (see Fig. 3). This will increase or decrease the pressure on the diaphragm and cause a corresponding change in the volume of sound produced by the horn.

45 While I have herein shown and described one embodiment of my invention for illustrative purposes and have disclosed and discussed in detail the construction and arrangement incidental to one specific application thereof, it is to be understood that the invention is limited neither to the mere details, or relative arrangement of parts, nor to its specific application herein shown, but that extensive deviations from the illustrative form or embodiment of the invention 50 may be made without departing from the principles thereof.

Having thus described one embodiment of my invention, what I claim is:—

60 1. An alarm or signaling apparatus having, in combination, a vibratory body, a casing for said body and means for vibrating said body including a power shaft, a bearing member for said shaft, and a support on 65 which said bearing member is mounted to

swing relatively to said casing about an axis transverse to the axis of rotation of said shaft.

2. An alarm or signaling apparatus having, in combination, a vibratory body, a casing for said body, means for vibrating said body including a power shaft, a bearing member for said shaft, a support on which said bearing member is mounted to swing relatively to said casing about an axis transverse to the axis of rotation of said shaft, and a driving member secured to said shaft. 75

3. An alarm or signaling apparatus having, in combination, a vibratory body, a casing for said body including a power shaft, a bearing member for said shaft, a support on which said bearing member is mounted to swing relatively to said casing about an axis transverse to the axis of rotation of said shaft, a driving member secured to said shaft, and means to swing said bearing member thereby to carry said driving member into engagement with suitable driving means. 80

4. An alarm or signaling apparatus having, in combination, a vibratory body, a casing therefor, a bearing member swiveled on said casing, and means for vibrating said body including a power shaft journaled in said member, said bearing being movable to 90 permit the oscillation of said shaft relatively to said casing.

5. An alarm or signaling apparatus having, in combination, a vibratory body, a casing therefor, a bearing member swiveled on 100 said casing, means for vibrating said body including a power shaft journaled in said member, and means for swinging said bearing member and shaft about the axis of said member. 105

6. An alarm or signaling apparatus having, in combination, a vibratory body, a casing therefor, a bearing member swiveled on said casing, means for vibrating said body including a power shaft journaled in said member, and yielding means for urging said bearing member in one direction about its axis, and means for swinging said bearing member about its axis in opposition to said yielding means. 110

7. An alarm or signaling apparatus having, in combination, a horn or resonator, a diaphragm, a casing for said diaphragm and means for vibrating said diaphragm including a power shaft, a bearing member for 120 said shaft, a casing in which said bearing member is mounted to swing about an axis transverse to the axis of rotation of said shaft.

8. An alarm or signaling apparatus having, in combination, a horn or resonator, a diaphragm, a casing for said diaphragm, and means for vibrating said diaphragm including a power shaft, a bearing member for 125 said shaft, a casing in which said bearing member is mounted to swing about an axis transverse to the axis of rotation of said shaft. 130

member is mounted to swing about an axis transverse to the axis of rotation of said shaft, and a driving member secured to said shaft.

5 9. An alarm or signaling apparatus having, in combination, a horn or resonator, a diaphragm, a casing for said diaphragm and means for vibrating said diaphragm including a power shaft, a bearing member for 45
10 said shaft mounted on said diaphragm casting to swing about an axis transverse to the axis of rotation of said shaft, a driving member secured to said shaft, and means to swing said shaft to carry said driving member 50
15 into driving connection with suitable driving means.

10. An alarm or signaling apparatus having, in combination, a diaphragm, a casing for said diaphragm, a bearing member swiveled upon and external of said casing, and means for vibrating said diaphragm including a power shaft journaled in said bearing member.

11. An alarm or signaling apparatus having, in combination, a diaphragm, a casing for said diaphragm, a bearing member swiveled on and external of said casing on an axis transverse to the plane of said diaphragm, and means for vibrating said diaphragm including a power shaft journaled in said bearing member.

12. An alarm or signaling apparatus having, in combination, a diaphragm, a casing for said diaphragm, a bearing member swiveled on said casing, on an axis transverse to the plane of said diaphragm, a power-shaft journaled in said bearing member and disposed at an angle to said axis, and means operated by said shaft for vibrating said diaphragm.

40 13. An alarm or signaling apparatus hav-

ing, in combination, a diaphragm, a casing for said diaphragm, a bearing member swiveled on and external of said casing on an axis transverse to the plane of said diaphragm, and means within said bearing member for vibrating said diaphragm. 45

14. An alarm or signaling apparatus having, in combination, a diaphragm, a casing for said diaphragm, a bearing member swiveled on said casing on an axis transverse to the plane of said diaphragm, a shaft journaled in said bearing member, a cam secured to said shaft within said bearing member, and a hammer interposed between said cam 55 and said diaphragm.

15. An alarm or signaling apparatus having, in combination, a diaphragm, a casing for said diaphragm, a bearing member provided with a hub swiveled in said casing, a 60 shaft journaled in said bearing member, a cam secured to said shaft within said bearing member, and a hammer interposed between said cam and said diaphragm.

16. An alarm or signaling apparatus having, in combination, a vibratory body, a rotary cam, a hammer interposed between said cam and said body, a casing for said vibratory body, a casing for said hammer and said cam, the second-mentioned casing being swiveled in the first-mentioned casing, a shaft bearing member secured to the second-mentioned casing, and a shaft to which said cam is secured, said shaft being journaled in said bearing member. 65
